No. 669,848.

Patented Mar. 12, 1901.

J. W. McMAHAN.

WASHING MACHINE.

(Application filed Sept. 22, 1900.)

(No Model.)

UNITED STATES PATENT OFFICE.

JOHN WESLEY McMAHAN, OF KANSAS CITY, MISSOURI.

WASHING-MACHINE.

SPECIFICATION forming part of Letters Patent No. 669,848, dated March 12, 1901.

Application filed September 22, 1900. Serial No. 30,828. (No model.)

To all whom it may concern:

Be it known that I, JOHN WESLEY McMAHAN, a citizen of the United States, residing at Kansas City, in the county of Jackson and State of Missouri, have invented certain new and useful Improvements in Washing-Machines: and I do hereby declare the following to be a full, clear, and exact description of the invention, such as will enable others skilled in the art to which it appertains to make and use the same.

This invention relates to a new and useful improvement in washing-machines; and it consists in the construction hereinafter set forth.

In the drawings, Figure 1 represents a perspective view of the device; Fig. 2 a vertical diametric section; Fig. 3, a horizontal section on the line 3 3, Fig. 2; Fig. 4, a partial section on the line 4 4, Fig. 2; Fig. 5, a detail of one of the side pieces.

In the drawings the letter A represents a suitable receptacle for containing the washing-frame B, made, preferably, cylindrical. This frame has the top b, bottom b', and the side pieces C secured at their upper ends c to the top b of the washing-frame B and to the bottom b' by the ends c'. The side pieces C are constructed as more particularly shown in Fig. 5, their upper parts c² being of full size, and extending down therefrom is a rib c', having an edge c⁴ turned toward the center of the frame. Secured to the under side of the top b of the washing-frame B are depending lugs d in pairs. Securely held between the lugs of each pair is the upper end d' of a strip D, which extends downwardly in the frame B, its lower end being loose or disconnected. These strips are flexible, being preferably made of rubber, and may be of any number. The bottom b' of the washing-frame B has upon its top surface radial channels b², extending from the center b³ and gradually enlarging in size, terminating at the edge of the bottom b', between the side pieces C, as clearly shown in Fig. 4.

The top b of the washing-frame B is provided with an opening b⁴, which is filled by a cover E, held to the top b by a hinge e.

Passing down through a hole e' of the cover 50 E is a vertical shaft f, on the bottom f' of which is secured a dasher F. This dasher F consists of a plate f², from which downwardly extend pins or projections f³. Above the cover E the shaft f is provided with a bevelled gear-wheel f⁴, which engages with a complementary bevelled gear g, secured to or made part of a handle G, which is pivoted in a bracket H, secured to one side of the cover E.

The washing-frame B, with its various 60 parts, is placed into the receptacle A. The water, clothes, and detergent are placed down into the frame B through the opening b⁴. The cover is closed, and the dasher is then reciprocated by means of the lever G. This 65 causes the contents of the washing-frame B to be thoroughly agitated. The clothes are thrown against the edges c⁴ of the side pieces C, and at the same time the strips D are moved about, whipping the clothes against 70 the sharp edges of the side pieces C. The dirt from the clothes falling to the bottom is guided by and along the channel b² out between the side pieces C, outside of the washing-frame B. If desired, the washing-frame 75 B may be supported upon feet b⁵. When this is done, there is a space between the bottom b' of the washing-frame B and the bottom of the receptacle A, within which the dirt will collect.

Having described my invention, what I claim is—

A washing-machine consisting of a receptacle, A, and a washing-frame, B, the latter having the opening in the top with the cover, 85 E, the dasher depending therefrom, and a handle above the cover for operating the dasher, and the side pieces, C, connecting the top and bottom of the washing-frame, such side pieces having the edges, c⁴, on the inner 90 side and the flexible strips, D, secured at one end only to the washing-frame, as set forth.

In testimony whereof I affix my signature in presence of two witnesses.

JOHN WESLEY McMAHAN.

Witnesses:

C. E. BROWNE,
J. H. BREMERMAN.
